UNITED STATES PATENT OFFICE.

JAMES SIMPSON, OF LIVERPOOL, COUNTY OF LANCASTER, ENGLAND.

LID FOR METALLIC DRUMS.

SPECIFICATION forming part of Letters Patent No. 374,276, dated December 6, 1887.

Application filed October 5, 1887. Serial No. 251,562. (No model.) Patented in England January 10, 1887, No. 334.

To all whom it may concern:

Be it known that I, JAMES SIMPSON, of Liverpool, in the county of Lancaster, England, have invented a new and useful Improvement 5 in Lids or Closers for Metallic Drums, (for which I have received Letters Patent in England, No. 334, dated January 10, 1887;) and I do hereby declare the following to be a full, clear, and exact description thereof.

10 This invention relates to improved lids or closers for metallic drums, which are secured to the vessels by means of lateral lugs or projections on the lid, which fit under the rim of the drum at the edges of the aperture thereof, 15 such as are described in the specification to my United States Patent No. 188,197, March 6, 1877.

It has been found in practice that when lids or closers such as are described in the specification above mentioned are used great care must be taken to make that part of the lid or closer next the lateral projections the exact size of the hole in the head of the drum, for if that part of the lid is larger than the hole 25 there is great difficulty in fixing the said lid or closer, and if smaller than the hole unclosed apertures are left at each side of the lateral projections.

Now, the object of my invention is to so 30 improve the said lids or closers that they may be small enough at the parts named to be easily fixed, and yet apertures will not be left at the points of junction of the lateral projections and lid or closer with the head of 35 the drum.

My invention consists in the combination, 40 with a lid for metallic drums having lateral projections which fit under the head of the drum and lock the lid in place over the filling-aperture, of a soft or elastic packing--such as string, cord, gutta-percha, soft-metal wire, and like substances--which is passed over the projections at their surfaces of juncture with the body of the lid, so that when 45 the lid is set in place and secured by means of the projections there shall be no vacant spaces at the edges of these projections.

Figure 1 is a plan, Fig. 2 a view of the under side, Fig. 3 a longitudinal section on the line $x-x$ of Fig. 1, and Fig. 4 a transverse section on the line $y-y$ of Fig. 2, of a lid or closer of the most approved construction under my invention. 1, body of lid; 2, lateral projec-

tions; 3, grooves in the under face of the lid or closer; 4, apertures at the extremity of the lid or closer; 5, string, cord, or other suitable packing. The string or cord passes over the upper edges of the lateral projections along the grooves in the under side and through the apertures 4.

Fig. 5 is a plan, and Fig. 6 an elevation, of a modification of my improved lid or closer; and Fig. 7 is a detail view of a part illustrating a modified form of my invention. 1, body of lid; 2, lateral projections; 5, string or cord 55 passed over the upper edges of the lateral projections and beneath the body of the lid, where the ends of the string are tied or secured at 6 to keep it in its place.

Instead of passing the string or its equivalent directly from one lateral projection to another, it may be made to cross, as shown by the dotted lines 7, the ends being brought to the crossing, where they are secured by cement--such as pitch--applied when melted.

Instead of one piece of string or its equivalent, two pieces may be used and the ends secured to the lid or closer by means of cement or other suitable adhesive substance. When metal is used, the ends are soldered or twisted 75 together or secured by clips, splicing, or in any suitable way. Rings or ferrules of soft metal, as shown in Fig. 7, may be made to fit over the lateral projections and be retained in position by friction or cement, the main feature 80 being the provision of a soft or resilient packing at the points of juncture of the lid or closer with the head of the drum or cask.

I claim—

1. The combination, with a lid or closer for 90 metallic drums having projections 2, which fit under the head of the drum and confine it in place, of a soft packing which is passed over the projections at their juncture with the body of the lid, substantially as and for the 95 purposes described.

2. In a lid or closer for metallic drums, the combination of the body 1, lateral projections 2, grooves 3, and apertures 4, with packing 5, for the purpose set forth.

In testimony whereof I have hereunto set my hand this 23d day of September, 1887.

JAMES SIMPSON.
